JOHN G. CALLAN, OF LYNN, MASSACHUSETTS, ASSIGNOR TO GENERAL ELECTRIC COMPANY, A CORPORATION OF NEW YORK.

GOVERNING MECHANISM FOR TURBINES.

No. 801,357.

Specification of Letters Patent.

Patented Oct. 10, 1905.

Application filed March 30, 1905. Serial No. 252,807.

To all whom it may concern:

Be it known that I, JOHN G. CALLAN, a citizen of the United States, residing at Lynn, in the county of Essex, State of Massachusetts, have invented certain new and useful Improvements in Governing Mechanism for Turbines, of which the following is a specification.

The present invention has for its object to improve the construction and operation of the mechanism employed for governing turbines or other motors.

My invention comprises a regulating mechanism which includes a primary means for determining the supply of steam or other motive fluid delivered to a turbine, with secondary means for automatically apportioning this steam whatever its amount among a plurality of nozzles in such manner as to use it with the maximum possible efficiency or to approximate this condition as nearly as possible. The primary means may be controlled by a speed-responsive device, by hand, electromagnetically, or otherwise and may in its simplest and preferred form consist of a throttle of any approved design. Its function is simply to determine the amount of motive fluid supplied without in any way affecting its distribution to the nozzles. The distributing or secondary means have primarily the function of keeping the minimum number of nozzles open at a given time which will afford passage for the quantity of steam determined in the manner just described, this condition being demanded by considerations of economy in that type of turbine in which the motive fluid is fed to the wheel by a plurality of nozzles. It will be noted that the varying back pressure consequent on the action of the distributing or secondary device will affect the functioning of the throttle if this be used as a device for fixing the supply of steam, and hence affect the speed-load characteristic. On the other hand, this distributing or secondary device may be used under conditions where this reaction does not occur—as, for example, in a low-pressure turbine using to best possible advantage all the exhaust of a reciprocating engine or high-pressure turbine.

In carrying out my invention one, two, or more valves are provided which respond to changes in pressure of the motive fluid and control its passage through nozzles or other

fluid-discharging devices. These valves may control the admission of fluid initially to the turbine or motor, or they may control the passage of fluid between any two or more stages of a multistage machine, or valves may be provided for both functions. Under normal conditions the valves open one after the other to admit fluid to the nozzles and close in reverse order to cut it off. Each valve is provided with a motor for opening and closing it which responds to changes in pressure of the motive fluid. These motors are of such a size or character and are so arranged that one valve opens at a definite predetermined pressure, a second valve at an increased pressure, and so on. Conversely, one motor closes its valve and then another, and so on. The motors should also be of such a character as to cause the valves to open sharply and promptly, so that the time during which they are close enough to their seats to cause cutting is extremely small. I prefer to operate these valves by diaphragms, since the latter possess certain advantages in the way of freedom from packing, absence of lubrication, &c. When the valves are diaphragm-actuated, the valve-stems move without sliding friction, and no frictional elements of any kind interfere with the action of the apparatus. This, among other things, permits of a close approximation to boiler-pressure in the inlet-chamber before the first valve and afterward each succeeding valve is brought into action, thereby increasing the average efficiency of the machine. Under certain conditions pistons may be substituted for the diaphragms; but I consider this to be less advantageous, since it would be necessary to lubricate and pack them, and they would leak to a certain extent.

It is preferable to provide each valve with two diaphragms or equivalent devices of different areas, the smaller one being subjected to the inlet or boiler pressure and the larger one to the pressure within some portion of the turbine, usually the steam-chest of the controlled nozzles. In other words, the pressure within the turbine tends to open the valves successively, and the inlet or boiler pressure acts as a weight therefor and tends to close them successively. In addition to and coöperating with the diaphragm-actuated admission-valves a throttle-valve is provided which is moved by a suitable speed-

responsive device driven directly or indirectly by the turbine-shaft. This valve by its action varies the pressure to which the larger diaphragms are subjected, and hence 5 controls the action of the fluid-pressure-actuated admission-valves. It is obvious that the load conditions will not always be satisfied by a given number of open and closed admission-valves—that is to say, two valves 10 may not admit enough fluid, while three valves will admit too much. The throttle-valve will take care of these intermediate load values by assuming different positions for different loads, and in this manner it is 15 possible to obtain a perfectly gradual increment of motive fluid for a gradual increase in demand for power. This obviates any tendency to a sudden increase in speed, especially in small machines, on the opening of 20 an additional valve. It is therefore possible to take advantage of the gain in economy due to the governing by progressive addition of nozzle-sections without incurring short life for the valves, as would be the case if the 25 governing were solely by their progressive action, or causing irregularities in speed, as would occur with the successive opening and closing of the governor-controlled valves communicating directly with the steam or 30 motive-fluid passage. The use of a throttle-valve also decreases the number of times that the admission-valves operate, thereby reducing the wear thereon. The throttle-valve normally opens more or less before each 35 admission or nozzle valve and closes more or less before each of said valves. In other words, it anticipates both the opening and closing of the admission-valves. The valve at which all throttling occurs is cheap, simple 40 in construction, easily replaced, and by its construction inherently adapted for throttling service and is therefore long-lived under conditions of operation. By using the boiler-pressure to weight the admission- 45 valves any reduction in pressure acts equally to reduce the tendency for the admission-valves to open and close. For example, with low boiler-pressure, as with normal, all of the valves may be brought into action 50 when the load requirements demand it. This is of further value in starting, since with the steam throttled by a hand-valve in the main supply-pipe and the throttle or governor-controlled valve wide open, as it would be at low speeds, the valves will all be wide 55 open, allowing the maximum acceleration.

In the accompanying drawings, which illustrate one embodiment of my invention, Figure 1 is a view, partially in section and partially in side elevation, of a turbine. Fig. 2 is a partial end elevation showing the location of the admission-valves, and Fig. 3 is a detail sectional view of a device for adjusting the percentage of boiler-pressure at which 60 the valves will open.

1 represents the casing of the turbine containing the bucket-wheel 2, having one or more rows of peripheral buckets 3. Where two or more rows of wheel-buckets are used, stationary intermediate buckets 4 are provided, which receive steam or other motive fluid from one row of wheel-buckets and discharge it against the next. The motive fluid is discharged against the wheel-buckets by one or more nozzles or other devices 5. The 75 nozzle preferably, but not necessarily, comprises a number of closely-associated discharge-passages having the same cross-section and angle of discharge. In the present 80 illustration of my invention four of these nozzles are provided, three of which have diaphragm-actuated valves, the fourth being always open.

The invention is shown in connection with a jet or impact type of turbine; but it is not 85 to be construed as being limited thereto. Fluid is admitted to the turbine by the valve-controlled conduit 6, the latter communicating with the passage or chamber 7, formed in the head of the wheel-casing. Located at 90 some suitable point between the conduit and the nozzle is a spring-closed shut-off or emergency valve 8, arranged to be tripped by a speed-responsive device when the speed of the bucket-wheel exceeds a definite amount. 95 Situated in the admission-passage 7 at a convenient point between the shut-off valve 8 and the nozzle or nozzles is a throttling-valve 9, which is moved by the speed-responsive device 10. The valve is of the piston type 100 and by its reciprocating movement varies the pressure of the fluid in chamber 7. It is shown in full-open position, as is also the shut-off valve.

The motive fluid is admitted to the nozzles by valves 11, of which three are shown; but the number can be varied as desired. The valves and their operating-motors being similar in construction, a description of one of them will suffice. The valve is attached to 110 a stem 12, and the latter is affixed to the low-pressure diaphragm 13 and the high-pressure diaphragm 14. On the valve-stem is a stop 15, which limits the movement of the valve-stem to the left. The stop should be so arranged that it does not cut off the admission of steam to the diaphragm-chamber. The chamber between the diaphragms is connected to atmosphere or other exhaust by the conduit 15^a. The low-pressure diaphragm is held against its seat by a nut 16, and the latter acts as a seat for the high-pressure diaphragm. The high-pressure diaphragm is held in position by a nut 17, the latter being externally threaded to receive 125 the cap 18. The end of the valve-stem may be provided with means, such as a nut or nuts, for cutting a valve out of service when for any reason it becomes desirable. The permanent opening of one of the admission- 130

valves would not seriously interfere with the governing, since the throttle-valve 9 controls the speed regardless of the number of valves open, providing only that this number is not reduced by some accident which leaves one or more permanently shut. The chamber 19 on the left of the high-pressure diaphragm is connected by the conduit 20 with the inlet or boiler pressure. The passage 10 of fluid through this conduit may be controlled by the valve 21. I may design the high-pressure diaphragm 14 to be subjected to the full boiler-pressure or a certain fraction thereof.

15 The operation of any one of the valves, assuming it to be closed, as shown, is as follows: There is tending to open the valve the more or less throttled pressure in the chamber 7 multiplied by the area of the diaphragm 13 and a constant. Tending to close the valve is the same throttled pressure multiplied by the area of the valve 11 plus the pressure in the inlet-pipe 6 multiplied by the area of the diaphragm 14 and a constant. 20 With pressures substantially equal in chambers 7 and 19 the pressure on diaphragm 13 will overcome that on diaphragm 14 and valve 11 and the latter will open. It will therefore be seen that when the turbine 25 is below speed, with the throttle-valve 9 wide open and the hand-operated throttle-valve in the conduit 6 either open or partially closed, the admission-valves will all be open and all of the nozzle-sections in action. This will be 30 the condition at starting and until a further increase in speed causes the valve to close. When the valve 11 is open, the forces acting upon the stem to close the valve are boiler-pressure in chamber 19 multiplied by the 35 area of the diaphragm 14 and a constant. Tending to hold the valve in this position is the pressure in chamber 7 multiplied by the area of diaphragm 13 and a constant. As the throttle-valve 9 closes and 40 reduces the pressure in the chamber 7 a certain point will be reached at which the boiler-pressure on the diaphragm 14, which has not been reduced, overcomes the pressure in chamber 7, despite the larger diaphragm 45 area upon which the latter operates and closes the valve. From this it follows that the valves 11 act to close a certain portion of the nozzle area when throttling has reduced the pressure in the chamber 7 to a predetermined point, this point being such as to indicate that portions of the nozzle area can safely be shut off. Immediately upon the shutting off of a nozzle by a valve 11, if the throttle-valve 9 be assumed to remain in a constant 50 position, the pressure in chamber 7 will rise, due to the decreased outflow area. This rise will not, however, cause the valve to open, since a new force tending to hold the valve closed has been created by reason of

the seating of the valve and the consequent 65 unbalanced pressures on its surfaces.

Assuming a minimum load with only that nozzle-section in service which has no valve, as the load progressively increases the throttle-valve 9 admits more steam, thus increasing 70 the pressure in the chamber 7. When the pressure therein becomes equal to the boiler-pressure, the turbine cannot carry further load without opening more nozzles. Hence the first valve should open before this 75 pressure is reached. For the purpose of illustration it may be assumed that this takes place when the throttled pressure reaches ninety per cent. of the boiler-pressure. The second valve may be arranged to open at 80 ninety-three per cent. and the third valve at ninety-six per cent. of the boiler-pressure. Where a greater number of valves is employed, the pressure differences between the 85 points of operation may be smaller.

In designing the diaphragms, valves, &c., care must be taken that the drop in pressure in chamber 7 due to the opening of a valve is not sufficient to cause the valve to immediately close again.

90 In Fig. 3 is shown a compression-spring 22 located within the cap 18 and pressing on the valve-stem. The stress on this spring can be adjusted by the movement of the screw 23, extending through the cap 18 and coöoperating with the nut 24 to adjust the percentage of boiler-pressure at which the valve will open. The effect of the spring is supplemental to the boiler-pressure and should be of relatively small amount.

95 In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

100 What I claim as new, and desire to secure by Letters Patent of the United States, is—

1. In a governing mechanism for an elastic-fluid motor, the combination of a primary means for determining the supply of motive fluid to the motor, with a subdivided secondary means for automatically apportioning the motive fluid to the fluid-discharging devices in accordance with the load.

115 2. In a governing mechanism for an elastic-fluid motor, the combination of a plurality of nozzles or fluid-discharging devices, primary means for determining the amount of motive fluid supplied to the motor, and a plurality of secondary or distributing means which receive the fluid after it has been acted upon by the primary means and distribute it 120 to the minimum number of nozzles or devices which will satisfy the demand for energy.

125 3. An elastic-fluid motor, in combination

with a plurality of independent and successively-acting valves for regulating the admission of motive fluid to the turbine, which respond automatically to changes in fluid-pressure, and a valve which operates between the opening and closing of the regulating-valves to take care of intermediate load values.

4. An elastic-fluid motor, in combination with a plurality of separately-actuated valves for regulating the admission of motive fluid to the turbine, which respond to changes in fluid-pressure, and a valve responding to speed changes of the motor, which varies the fluid-pressure and causes the valves to operate in predetermined order and also regulates the fluid passing to the motor.

5. In a governing mechanism for elastic-fluid turbines, the combination of a plurality of regulating-valves which open and close one after the other in response to changes in fluid-pressure, and a valve acting between the opening and closing of each of said pressure-actuated valves, which assists in varying the volume of fluid passing to the motor and at the same time determines the opening and closing of the regulating-valve.

6. In a governing mechanism for elastic-fluid motors, the combination of a movable element, valves responding to pressure variations for regulating the admission of fluid to the rotating element, and a valve also acting on the fluid passing to the element and responding to speed variations thereof for controlling the admission-valves.

7. In a governing mechanism for elastic-fluid motors, the combination of a movable element, a plurality of successively-acting valves for regulating the admission of fluid to the rotating element, and a valve which assists in regulating the admission of fluid to the rotating element and also controls the action of the successively-operating admission-valves.

8. In a governing mechanism for elastic-fluid motors, the combination of a movable element, successively-acting valves regulating the admission of fluid thereto, the valves being acted upon by the pressure of the source of supply and also by that entering the rotating element, and a throttle-valve which regulates the admission of fluid to the rotating element and also controls the successive action of the admission-valves.

9. A turbine comprising relatively movable elements, in combination with an admission-valve for admitting motive fluid to the turbine, the said valve being urged toward its seat by the pressure of the fluid admitted to the turbine, and a throttle-valve located between the source of supply and the turbine which, in addition to regulating the pressure of the source of supply, controls the movements of the admission-valve.

10. A turbine comprising relatively movable elements, in combination with a plurality of successively-acting admission-valves which are subjected to the boiler-pressure and also to the inlet-pressure, and a valve responding to speed changes of the turbine for regulating the inlet-pressure and also the opening and closing of the valves.

11. A turbine comprising relatively rotat- 65 ing parts, in combination with a plurality of independent and successively-actuated valves which respond to changes in fluid-pressure, and a valve acting on the main fluid-supply which regulates the admission of fluid to the turbine between the opening and closing of each two of said valves. 70

12. A turbine comprising relatively rotat- 75 ing parts, in combination with a plurality of independent and successively-actuated valves which are subject to boiler and inlet pressures, and a valve acting on the main fluid-supply which regulates the admission of fluid to the turbine between the opening and closing of each two of said valves and also controls the successive actuation of the valves. 80

13. In combination, a turbine, a passage for conveying motive fluid thereto, a throttle-valve located in said passage for controlling the admission of fluid to the turbine, individual and successively-acting valves 95 which are located beyond the throttle-valve and also control the admission of fluid to the turbine, and motors for operating the valves which depend for their action upon the difference between the supply and inlet pres- 100 sures as created by the throttle-valve.

14. In a governing mechanism for elastic-fluid turbines, the combination of a plurality of independent and successively-acting valves for regulating the admission of fluid 105 to the turbine, a separate motor for operating each of the valves, conduits for subjecting the motors to the pressure of the source of supply, conduits for subjecting the motors to an opposing inlet-pressure, and a 110 throttle-valve which varies the inlet-pressure as the demand for fluid changes.

15. In a governing mechanism, the combination of an admission-valve, high and low pressure diaphragms for closing and 115 opening the valve, a conduit for conveying fluid to the high-pressure diaphragm, another conduit for conveying fluid to the low-pressure diaphragm, and a valve for varying the pressure of the fluid acting on the 120 low-pressure diaphragm.

16. In a governing mechanism, the combination of a plurality of successively-acting admission-valves, high and low pressure diaphragms for closing and opening the valves 125 one after the other, conduits for conveying fluid to the high and low pressure diaphragms, and a valve responding to speed

changes, which varies the pressure to which the diaphragms are subjected.

17. In a governing mechanism, the combination of a plurality of successively-acting admission-valves which open and close in response to pressure variations, and a throttle-valve the action of which precedes the opening or closing of each of the admission-valves.
18. In combination, a turbine, devices for discharging fluid against the moving buckets, admission-valves sensitive to pressure variations for regulating the admission of fluid to the devices, which are less in number than said devices, and a throttle-valve which regulates the passage of fluid to the un-

valved device and also controls the action of the admission-valves.

19. An elastic-fluid motor, in combination with a plurality of separately-actuated valves for regulating the admission of motive fluid to the turbine, and a valve which controls the operation of the separately-actuated valves and in addition thereto regulates the supply of fluid to the motor. ²⁰

In witness whereof I have hereunto set my hand this 28th day of March, 1905.
